ATTORNEY.

UNITED STATES PATENT OFFICE.

AUGUSTUS DE ST. GEORGE, OF CHICAGO, ILLINOIS.

DESIGN FOR A DECANTER.

SPECIFICATION forming part of Design No. 34,095, dated February 19, 1901.

Application filed January 24, 1901. Serial No. 44,681. Term of patent 7 years.

To all whom it may concern.

Be it known that I, AUGUSTUS DE ST. GEORGE, a citizen of the United States, residing at Chicago, in the county of Cook and 5 State of Illinois, have invented and produced a new and original Design for Decanters, of which the following is a specification, reference being had to the accompanying drawing, forming a part thereof, and in which the figure is a side elevation of a decanter, showing my new design.

As shown in the drawing, the leading or material features of my design consist of a decanter having its lower portion formed in 15 the shape of a semiglobe, as shown at A, forming the lower side portion of the decanter. The upper side portion of the decanter is formed with a straight inward incline extending from the upper edge of the

semiglobular portion and terminating in the 20 neck portion, as shown at B.

C designates the neck portion of the decanter. On this neck portion of the decanter are a series of flutes, as shown at D. These flutes extend entirely around the neck and 25 commence from the lower portion of the neck and extend to a point adjacent the top thereof.

Having thus described my invention, what I claim as new, and desire to secure by Letters Patent, is—

30 The design for a decanter, substantially as shown and described.

In testimony whereof I have hereunto set my hand in the presence of two witnesses.

AUGUSTUS DE ST. GEORGE.

Witnesses:

CHAS. HULSMAN,

JOHN W. BENDER.
